UNITED STATES PATENT OFFICE.

HALLVARD NÆSS, OF MOSS, NORWAY.

APPARATUS FOR CLEANING CENTRIFUGAL SEPARATORS.

Application filed July 14, 1926, Serial No. 122,470, and in Norway June 18, 1925.

In all centrifugal separators hitherto used, wherein sets of plates are used, the set of plates must, after the separating operation, be cleaned and dried carefully in order to remove deposited impurities and to prevent the rusting of the plates. This is effected either by separating the plates from one another and cleaning the several plates and the distributing cross separately, or the cross is placed in the bowl body of the separator, after having cleaned the same from dirt, and the impurities of the plates are flung out into the bowl body, whereupon the separator must again be stopped and the bowl body be cleaned anew. This cleansing has also been effected by simply immersing the plate set of the centrifugal separators in a cleansing fluid and rotating said plate set in the liquid. These operations are very time-wasting, and in case of a continuous separation the work rendered by the separator is considerably reduced on account of this slow cleaning process. Thereby the practical use of the centrifugal separators is rather limited.

The present invention has for its object the provision of an apparatus for centrifugally cleaning the plate set and the distributing cross tending to shorten the cleaning period and obtain simultaneously a complete cleaning of plate set and distributing cross. In the following the invention will be described with reference to the annexed drawing showing a sectional view of an apparatus in accordance with my invention.

In order to clean the plate set 2 the same together with the distributing cross 3 are taken out from the bowl body and are placed within a special cleaning bowl body 4 which may be set in rotation by means of a spindle 1. The cylindric part (wall) of this bowl body is, contrary to the solid walls of the ordinary bowl bodies, perforated by slots 9, holes or the like.

For the complete cleaning of plates and cross a cleaning medium must be supplied, which is supplied to the plate set by the same path as that by which the lightest liquid leaves the plate set during the separating operation (at the inner edges of the plates).

The cleaning medium is supplied either by means of a special top piece 5 placed on the

top of the plate set and so constructed that the cleaning medium through the channels of the distributing cross and through the inner holes of the plates flows in between the plates, or the ordinary top piece (upper plate with neck) is retained. In such case the said piece must be of such a construction that the outlet apertures in the neck may also serve as a receiver for the cleaning medium. Either top piece keeps the hole cleaning device together by being screwed fast to the cleaning bowl body by means of a nut 6. The cleaning medium is introduced into the neck of the top piece by means of a hopper 7, pipe or the like. This supply is so arranged that alternately or simultaneously the cleaning medium may be supplied to the interior or/and exterior of the distributing cross.

During the rotation the cleaning medium is flung out against the bowl body between the plates and cleans the same from within outwardly. On account of the bowl body being perforated the cleaning medium and all impurities are flung out through the aperture of the cleaning bowl body but are prevented by a shield 8 from being flung out into the space.

With this cleaning apparatus the whole plate set can be cleaned and dried completely in a minimum of time.

The cleaning medium may be in a liquid or a gaseous state, and if desired a special drying medium may be used after accomplished cleaning.

Claim:

Apparatus for centrifugal cleaning of the plate set and the distributing cross of centrifugal separators, comprising a bowl body for receiving the set of separator plates and distributing cross to be cleansed, means for rotating said bowl said distributing cross and the plate set carried thereby, a top piece for supplying the cleaning medium to the inner edges of said separator plates, and means for allowing said cleaning medium together with the impurities removed thereby to escape from said bowl.

In testimony whereof I have signed my name to this specification.

HALLVARD NÆSS.
